COLOR LIGHT MIXER FOR A PHOTOGRAPHIC ENLARGER

Robert A. Flieder, Englewood Cliffs, N.J., and James T. Aneshansley, Brooklyn, N.Y., assignors to Berkey Photo, Inc., New York, N.Y.

Filed Feb. 4, 1972, Ser. No. 223,804

Term of patent 14 years

Int. Cl. D16—03

U.S. Cl. D61—1 Q

FIG. 1

FIG. 2

FIG. 3

FIG. 4

FIG. 1 is a top front isometric view of a color light mixer for a photographic enlarger showing our new design;

FIG. 2 is a bottom front isometric view thereof;

FIG. 3 is a top plan view thereof;

FIG. 4 is a rear elevational view thereof.

We claim:

The ornamental design for a color light mixer for a photographic enlarger, as shown.
